UNITED STATES PATENT OFFICE.

JOHN A. BODKIN, OF NEW YORK, N. Y., ASSIGNOR TO OTTO R. BARNETT, OF GLENCOE, ILLINOIS.

RAIL-ANCHOR.

973,160.

Specification of Letters Patent. Patented Oct. 18, 1910.

Application filed July 6, 1909. Serial No. 506,083.

To all whom it may concern:

Be it known that I, JOHN A. BODKIN, a citizen of the United States, residing at New York city, in the county of New York and State of New York, have invented certain new and useful Improvements in Rail-Anchors, of which the following is a specification.

My invention relates to a device for preventing the longitudinal movement or creeping of the rails of a railroad, devices of this sort being ordinarily called rail anchors, rail stays or anti-creepers; and the invention has for its object to provide a new and improved construction for devices of this character.

The principal object of the invention is to provide a rail anchor in which one of the jaws which grip the rail on opposite sides is in the form of a rotating cam, which bears against the rail flange in such a manner that any tendency on the part of the rail to creep will be checked by the increased gripping pressure brought about by the rotation of the cam. While the invention will be illustrated and described in constructions involving the use of such a cam on one side of the rail only, the ordinary jaw being employed on the other end of the stay, it is obvious that the cam arrangement could be used on each side of the rail, if desired.

The invention has for a further object to provide means for locking the cam against reverse rotation, thereby preventing the engagement between the stay and the rail from being loosened by the slight reactive movement, or rebound, of the rail, which occurs after the train has passed over the same, and which prevents a loosening of said engagement, due to any accidental cause.

The invention has for further objects such other new and improved constructions in rail anchors as will be described in this specification and particularly set forth in the claims appended thereto.

Certain preferred embodiments of the invention are shown in the accompanying drawings, in which—

Figure 1 is a plan view illustrating one form of rail stay constructed in accordance with my invention. Fig. 2 a sectional view on line 2—2 of Fig. 1, looking in the direction of the arrows. Fig. 3 a side elevation,

enlarged, of the cam. Fig. 4 an inverted plan view of the same. Fig. 5 a fragmentary plan view illustrating a modified structure. Fig. 6 a section taken on line 6—6 of Fig. 5. Fig. 7 a fragmentary plan view illustrating a different embodiment of the ideas involved in the two preceding figures. Fig. 8 a vertical section illustrating a somewhat different form of device. Fig. 9 a plan view of the cam shown in Fig. 8. Fig. 10 an inverted plan view of the nut. Fig. 11 a view in perspective of the locking device. Fig. 12 a plan view illustrating another modification. Fig. 13 a section on line 13—13 of Fig. 12. Fig. 14 a fragmentary plan view of the body of the stay shown in the preceding two figures. Fig. 15 an inverted plan view of the cam, and Fig. 16 a section taken on line 16, 16 of Fig. 13.

Like characters of reference indicate like parts in the several figures of the drawings.

Referring first to Figs. 1 to 4 inclusive, which show the simplest form of the invention, A represents the rail, having the usual flange B, and C one of the ties supporting the rail. The stay or anchor consists of a body part or bar D, which extends under the base or flange B of the rail and which abuts against the tie. In order to get a firm bearing upon the tie, the bar may be provided with the depending flange E. The rail is gripped between the rotating cam F on one end of the bar D and the jaw G on the other end. The latter may conveniently, though not necessarily, be integral with the bar. The cam F consists preferably of a circular disk eccentrically mounted on a bolt H with its vertical edge f, which is preferably serrated or roughened, bearing against the edge of the rail flange. The cam is held to the body of the stay D by a nut I. A washer i may be interposed between the nut and the cam. Preferably, the cam is formed with an overhanging rim f' and the edge of this rim may be roughened in order that the stay may be tightened on the rail by hammering.

It will be understood that when the stay has been clamped upon the rail flange with the abutment E against a tie, on the side of the tie from which the trains approach, the tendency of the rail to creep under the action of the train will be resisted by the cam, which, by rotating with the advance of the

rail, causes the rail stay to grip the rail with additional force.

In Figs. 5 and 6 I have shown a modification affecting only the structure of the cam. In this construction the eccentrically placed opening f^2 of the cam F' is threaded, the bolt H' being correspondingly threaded. The nut of the previously described construction may, therefore, if desired, be dispensed with. In this form of device I have shown means for preventing a reverse rotation of the cam. It has been found that rails have a tendency to react or rebound slightly after a train has passed over them the rebound being, of course, in the direction opposite to the creep of the rail. This tendency, slight as it is, is sufficient to loosen the grip upon the rail of certain types of rail stay. To overcome this tendency in the stay of my present invention, I provide locking means which permits a free rotation of the cam forward (relatively to the rail), while preventing a reverse movement. For example, a recess J , wider at one end than at the other, may be formed upon the circumference of the opening f^2 and a threaded pin K inserted in the wider part of this recess. Supposing the tendency of the rail to be to creep in the direction indicated by the feathered arrow in Fig. 5, the pin K will allow cam F' to rotate with the advance movement of the rail in a direction to increase the distance between the opening f^2 and the edge of the rail flange while locking the cam from reverse rotation.

In the drawings the pin K is shown as resting in the wider end of the recess J , so that the pin K will freely rotate when the cam is turned in the direction indicated by the arrows, but when the cam is turned in the opposite direction the pin K will be brought in contact with the narrower end of the recess J , which is of such dimension that the pin K will be tightly wedged against the central bolt H' , so as to prevent such reverse rotation of the cam.

The top f^3 of cam F' is shown in Fig. 5 as hexagonal in form. This is to allow the cam to be tightened by a wrench. The modification illustrated in Fig. 7 shows the top f^4 of the cam as circular, as in the construction of the first four figures. Otherwise, the device of Fig. 7 is the same as that of Figs. 5 and 6.

In Figs. 8 to 11 inclusive, I have shown a further modification involving, however, the same general principles. The cam F^2 in this case turns upon a sleeve L which surrounds the bolt H^2 . The nut I^2 is provided with the notches M on its under surface, and the cam has corresponding notches N . Between the nut and the cam is interposed a spring lock O with its ends o, o' turned in opposite directions. The engagement of the spring lock with the notches M and N is such as to

permit the cam to be turned in the direction of the creep of the rail, but to prevent reverse rotation.

A somewhat different form of device is shown in Figs. 12 to 16 inclusive. Here the tie abutment E^3 is shown as on the opposite end of the stay D^3 from jaw G^3 . The position of the abutment, however, is not essential to any particular form of device. The cam F^3 of Figs. 12 to 16 inclusive, turns on a sleeve L^3 on the bolt H^3 . The under side of cam F^3 is provided with the notches M^3 and the upper surface of the stay with the notches N^3 . A spring lock O^3 , similar to the spring lock of Fig. 11 may be interposed between the cam and the body of the stay. The parts are held together by the nut I^3 .

I do not limit myself to the particular forms, constructions and devices shown and described, as modifications might be devised which would come within my invention as defined by the claims.

I claim:

1. A rail stay comprising means which extends under the rail, engages one edge of the flange thereof and abuts against a tie upon which the rail is supported, in combination with a cam which engages the other side of the rail flange in such way that the tendency of the rail to move longitudinally in one direction increases the lateral pressure of the cam upon the rail and means for preventing reverse movement of the cam.

2. A rail stay comprising means which extends under the rail, engages one edge of the flange thereof and abuts against a tie upon which the rail is supported, in combination with a rotatable cam which engages the other side of the rail flange, so that the tendency of the rail to move longitudinally in one direction increases the lateral pressure of the cam upon the rail and means for preventing reverse movement of the cam.

3. A rail stay comprising means which extends under the rail, engages one edge of the flange thereof and abuts against a tie upon which the rail is supported, in combination with a cam which engages the other side of the rail flange in such way that the tendency of the rail to move longitudinally in one direction increases the lateral pressure of the cam upon the rail and means for preventing reverse movement of the cam, said cam having a substantially vertical edge which is serrated.

4. A rail stay comprising means which extends under the rail, engages one edge of the flange thereof and abuts against a tie upon which the rail is supported, in combination with a cam which engages the other side of the rail flange in such way that the tendency of the rail to move longitudinally in one direction increases the lateral pressure of the cam upon the rail and means for preventing reverse movement of the cam, said cam hav-

ing a part which overhangs the edge of the rail flange.

5. A rail stay comprising means which extends under the rail, engages one edge of the flange thereof and abuts against a tie upon which the rail is supported, in combination with a cam which engages the other side of the rail flange in such way that the tendency of the rail to move longitudinally in one direction tends to shift the cam with respect to the stay and so increases the lateral pressure of the cam upon the rail, and means for locking the cam against reverse movement.

6. A rail stay comprising means which extends under the rail, engages one edge of the flange thereof and abuts against a tie on which the rail is supported, in combination with a cam rotatably mounted on said aforementioned means so as to engage the opposite edge of said rail flange and engaging means for the cam which permits the rotation of the cam in the direction to increase the grip of the stay on the rail but prevents reverse rotation.

25 7. A rail stay comprising a bar extending under the rail flange and provided with an abutment for a tie, a jaw on one end of said bar which engages one edge of the rail flange, a bolt extending through the other end of said bar, and a circular disk which is eccentrically and rotatably mounted on said bolt and which engages the other edge of said rail flange.

8. A rail stay comprising a bar extending under the rail flange and provided with an abutment for a tie, a jaw on one end of said bar which engages one edge of the rail flange, a bolt extending through the other end of said bar, a circular disk which is eccentrically and rotatably mounted on said bolt and which engages the other edge of said rail flange, said disk having a vertical edge and an overhanging part which engages the top of the rail flange.

45 9. A rail stay comprising a bar extending under the rail flange and provided with an abutment for a tie, a jaw on one end of said bar which engages one edge of the rail flange, a bolt extending through the other end of said bar, a circular disk which is eccentrically and rotatably mounted on said bolt and which engages the other edge of said rail flange, and means for preventing the rotation of the disk in one direction while permitting its rotation in the opposite direction.

10. A rail stay comprising means which extends under the rail, engages one edge of the flange thereof and abuts against a tie on which the rail is supported, in combination with means rotatably mounted thereon which engages the rail on the opposite side, and means which permits the rotation of

said rotatable means in the direction to increase the grip of the stay on the rail but prevents reverse rotation.

11. A rail stay comprising means which extends under the rail, engages one edge of the flange thereof and abuts against a tie on which the rail is supported, in combination with means rotatably mounted on the aforesaid means which engages the rail on the other side, and a spring lock which engages said rotatable means so as to permit the rotation thereof in the direction to increase the grip of the stay on the rail, but prevents reverse rotation.

12. A rail stay comprising means which extends under the rail, engages one edge of the flange thereof and abuts against a tie on which the rail is supported, in combination with a cam rotatably mounted on the aforesaid means so as to engage the opposite edge of said rail flange, and a spring lock which engages said cam so as to permit the rotation of the cam in the direction to increase the grip of the stay on the rail, but which prevents reverse rotation.

13. A rail stay comprising means which extends under the rail, engages one edge of the flange thereof and abuts against a tie on which the rail is supported, in combination with a cam which engages the opposite edge of the rail flange, a bolt on which said cam is mounted, a nut on said bolt, said nut and cam having teeth on their opposite surfaces, and a spring lock interposed between said nut and cam which engages said teeth, for the purpose specified.

14. A rail stay comprising means which extends under the rail, engages one edge of the rail thereof and abuts against a tie on which the rail is supported, in combination with a cam which engages the opposite edge of said rail flange, a bolt on which said cam is mounted, a sleeve interposed between the bolt and the cam, a nut which abuts against the sleeve, said nut and cam having teeth on their opposed surfaces, and a spring lock interposed between the nut and the cam which engages the said teeth, for the purpose specified.

15. A rail stay comprising a body part which extends under the rail flange having an integral jaw and an integral abutment for a tie on one end thereof, in combination with a cam rotatably mounted on the opposite end of said body part, and engaging means which permits the rotation of the cam in the direction to increase the grip of the stay on the rail but prevents reverse rotation.

JOHN A. BODKIN.
